RADIATOR

Filed Oct. 22, 1924

Fig. 1

UNITED STATES PATENT OFFICE.

SUMNER BOYD CHILSON, OF MINNEAPOLIS, MINNESOTA.

RADIATOR.

Application filed October 22, 1924. Serial No. 745,112.

My invention relates to improvements in radiators for automobiles.

An object of the invention is to provide an improved radiator for water cooling systems for internal combustion engines of automobiles, said radiators being formed with an egress conduit incorporated in the radiator structure, the intake to said conduit being arranged to provide for maximum efficiency 10 in the use of the radiator, and the outlet being arranged to provide for easy access to the radiator for the purpose of dismantling the automobile or for the purpose of repairing the radiator.

With the foregoing and other objects in view, which will appear in the following description, the invention resides in the novel combination and arrangement of parts and in the details of construction hereinafter 20 described and claimed.

In the drawings, Fig. 1 is an elevational view illustrating the back of a radiator embodying my invention, a portion of the radiator being broken away to disclose parts 25 otherwise concealed, and Fig. 2 is a vertical sectional view taken on the line 2—2 of Fig. 1.

Referring to the drawing, it will be seen that my improvement includes a core A, top 30 tank 10, bottom tank 11 and shell 12. The core A may be of any of the usual types embodying ducts for the passage of water therethrough and fins associated with said ducts for cooling the same. In the present 35 disclosure upright tubes 13 constitute the ducts and thin horizontal sheets 14 comprise the cooling fins. A multiplicity of tubes 13 are employed, the same being snugly fitted in and secured to the fins 14 intersected thereby. The upper ends of the tubes 13 40 are secured in the bottom of the tank 10 and open therethrough into said tank, while the lower ends of said tubes are secured in the top of the tank 11 and open through said top into said tank 11. The unitary 45 structure thus afforded by said core A and tanks 10, 11 is framed by the shell or case 12. The upper tank 10 is equipped with the usual filler-neck 15, cap 16 for said neck,

ingress hose connection 17 and vent tube 18. 50

The ordinary automobile radiator has an egress hose connection medially of the ends of the lower tank and at the back or bottom thereof. In such position this hose connection is exceedingly difficult to reach and it 55 locates the hose-nipple attached thereto in a place wherein the accumulation of deteriorating oil and grease on the hose is greatest. This condition existing, the lower hose-nipples require frequent replacement with the 60 attendant expenditure of much time and labor, which expenditure of time and labor is also required in the simple step necessary preparatory to the removal of the radiator 65 for repair or to permit of access to parts of the automobile adjacent thereto. I, therefore, omit the usual lower hose connection and in its stead supply an egress conduit 19 within the bottom of the tank 11, a pipe 20

rising from said conduit through the core A 70 and a hose connection 21 issuing rearward from the upper end of said pipe 20 at one side-margin of the radiator. Thus located, said hose connection 21 is readily accessible and in most instances holds the rear hose-nipple in position comparatively free from the accumulation of oil and grease. In arranging the conduit 19 and pipe 20 to locate the hose connection 21, as above explained, I have provided for maximum temperature 75 reducing capacity of the radiator. The conduit 19, preferably an integral part of the lower tank 11, opens at the bottom of said tank midway between the ends thereof, said conduit being extended to one end of the 80 tank, thence turned upward to the top thereof. Fitted at its lower end in the upper end of said conduit 19, the pipe 20 rises through the fins 14. These fins fit snugly around the pipe 20, the hose connection 21 on said pipe 85 being turned rearwardly in the core A and reaching back therefrom at a point approximately midway between the top and bottom of the core and in the margin at the side thereof. Thus it will be understood that the conduit 19 drains the tank 11 from a central point therein; that the core fins 14 serve as 90 cooling elements for the pipe 20 and pipe 95

connection 21, and that said connection is disposed so as to be easily accessible and to locate the complementary hose-nipple in position free from accumulations of oil and grease. Covering an opening 22 formed in the bottom of the tank 11 directly beneath the inner extremity of the conduit 19 is a cover plate 23. This cover plate may be removed by unscrewing the attaching screws 10 24 to permit of the insertion of an instrument through the opening 22 and into the conduit 19 for cleaning said conduit. Said cover plate 23 may also be removed to permit of the draining of the radiator when a 15 larger drain than that afforded by the conventional drain-cock 25 is desired.

The radiator is applied to an automobile chassis in the usual manner, stud blocks 26 being provided on the underside of the tank 20 11 for attachment to the chassis frame. The hose connection 17 is connected as usual through a conventional hose-nipple with the feed side of the water pump of the engine, and the hose connection 21 is likewise connected with the return side of said pump.

Changes in the specific form of my invention, as herein disclosed, may be made within the scope of what is claimed without departing from the spirit of my invention.

30 Having described my invention, what I claim as new and desire to protect by Letters Patent is:

1. In a radiator, a core including ducts for the passage of water therethrough and 35 fins associated with said ducts for cooling the same, a tank at the top of the core feeding into said ducts, a tank at the bottom of the core into which said ducts empty, an egress conduit embodied in the lower tank 40 structure, said conduit opening midway between the ends of said tank at the bottom thereof and extending along said bottom to one end of the tank and within the same and thence upward to the top of the tank, and 45 a pipe rising through the core from said conduit to a point substantially medially of the top and bottom of said core, said pipe having a fitting turned rearwardly through the core and accessible at the back thereof, 50 the fins of the core providing cooling elements for said pipe and fitting.

2. In a radiator, a core including ducts for the passage of water therethrough and 55 fins associated with said ducts for cooling the same, a tank at the top of the core feeding into said ducts, a tank at the bottom of the core into which said ducts empty, an egress conduit within the lower tank structure, said conduit opening between the ends 60 of said tank and extending longitudinally thereof to one of its ends, and a pipe rising from said conduit through the core to a point between the top and bottom thereof, said pipe having a fitting turned rearwardly through the core and accessible at 65

the back thereof, the fins of the core providing cooling elements for said pipe and fitting.

3. In a radiator, a core including ducts for the passage of water therethrough and 70 fins associated with said ducts for cooling the same, a tank at the top of the core feeding into said ducts, a tank at the bottom of the core into which said ducts empty, and an egress pipe rising through the core 75 from the lower tank to a point between the top and bottom of said core, said pipe having a fitting turned rearwardly through the core and accessible at the back thereof, the fins of the core providing cooling elements 80 for said pipe and fitting.

4. In a radiator, a core including ducts for the passage of water therethrough and 85 fins associated with said ducts for cooling the same, a tank at the top of the core feeding into said ducts, a tank at the bottom of the core into which said ducts empty, and an egress pipe connected with and issuing 90 upwardly from the bottom tank, said pipe extending through said fins and braced thereby and having a fitting at its upper end accessible at the back of said core.

5. In a radiator, a core, a tank at the top of the core feeding into the same, a tank at the bottom of the core into which said core empties, and an egress pipe connected with and issuing upwardly from the lower tank within said core to a point between the top and bottom thereof, said pipe being 95 rigidly braced in all lateral directions by the core and accessible at its upper end at the rear of said core.

6. In a radiator, a core, a tank at the top of the core feeding into the same, a tank at the bottom of the core into which said core empties, an egress conduit communicating at its lower end with the lower tank at a point between the ends thereof and within the same said conduit leading upwardly through the core and braced thereby 105 and accessible at the rear thereof at an elevation between the top and bottom of said core.

7. A radiator structure including a core, a tank at the top of the core feeding into the same, a tank at the bottom of the core into which said core empties, an egress conduit within the lower tank, said conduit opening between the ends of said tank and extending longitudinally thereof to one of its ends, a shell encasing the upright edges of the core, a pipe rising from said conduit inside of said shell and between the planes of the front and rear faces of said core, said pipe being braced by the structure at its upper end and having a fitting at said end thereof accessible at the rear of the core.

8. In a radiator structure including a core, an upper tank at the top of the core feed- 110

ing into the same, a lower tank at the bottom of the core into which said core empties and a shell encasing the upright edges of the core, an egress pipe connected with 5 and issuing upwardly from the lower tank between the planes of the front and rear faces of said core and having an outlet fitting at its upper end accessible at the rear of the core between said upper and lower tanks, said egress pipe being rigidly braced 10 by the structure remotely from the lower tank.

In testimony whereof, I have signed my name to this specification.

SUMNER BOYD CHILSON.
